UNITED STATES PATENT OFFICE.

ROGERS E. MOIST, OF SPRINGFIELD, MISSOURI.

HAIL-PROOF WIRE-WOVEN ROOFING OR SHEATHING.

1,362,887.

Specification of Letters Patent. Patented Dec. 21, 1920.

Application filed June 6, 1919. Serial No. 302,151.

To all whom it may concern:

Be it known that I, ROGERS E. MOIST, a citizen of the United States, residing at Springfield, in the county of Greene and State of Missouri, have invented certain new and useful Improvements in Hail-Proof Wire-Woven Roofing or Sheathing, of which the following is a specification, reference being had therein to the accompanying drawings.

This invention relates to an improved roofing, and more particularly to a hail-proof, wire-woven roofing, or sheathing.

The object of the invention is the production of a very efficient and durable roofing that is made of a composition reinforced by a wire mesh.

Another object of the invention is the construction of a roofing of different layers of a peculiarly-compounded material, and interposed between these layers is a metal mesh or a metal layer.

With these and other objects in view, my invention comprises certain combinations of ingredients and the arrangement of layers as will be more specifically pointed out in the following description, and clearly illustrated in the accompanying drawings.

In the drawings,

Figure 1 is a perspective view of a piece of my improved roofing, showing one corner of a layer turned up to reveal the position of the wire mesh therein.

Fig. 2 is an edge view in elevation of my improved roofing.

Referring to the drawings by numerals, 1 designates the inner layer, 2 is the wire mesh, and 3 is the outer or top layer; the

inner layer 1 is provided with an inner, smooth surface 4, while the upper or outer layer 3 is provided with a roughened or sandpaper-like surface 5.

The body of layers 1 and 3 is composed of rags, cotton, wool, liner, felt, silk, or plant fiber, oil, coal tar products, asbestos, wood pulp, rubber, and asphalt. It is to be understood that my finished product or roofing involves the metal wire or mesh 2 as a part as much as any other ingredient, and going to produce a homogeneous mass that results in a very strong, durable, and long-lived roofing.

I wish it to be understood that I reserve the right to make such minor alterations or changes in the manufacture of my roofing as shall appear to one skilled in the art to which this invention relates, which changes or alterations shall fairly fall within the scope of the appended claims.

What I claim is:

1. A roofing of the class described, comprising cotton, wool, linen, silk, oil, coal-tar products, asbestos, wood pulp, rubber, asphalt, and metal wire.

2. As a new article of manufacture a roofing of the class described comprising a body having in the center thereof a wire mesh and a body consisting of cotton, wool, linen, silk, oil, coal tar products, asbestos, wood pulp, rubber and asphalt, and said body provided with a smooth inner surface and with a rough sandpaper-like outer surface, substantially as shown and described.

In testimony whereof I hereunto affix my signature.

ROGERS E. MOIST.
